CHARLES H. SISSON AND SIMON P. KELCH, OF NELSONVILLE, OHIO.

CAR-REPLACER.

1,121,301.

Specification of Letters Patent.

Patented Dec. 15, 1914.

Application filed July 31, 1914. Serial No. 854,347.

To all whom it may concern:

Be it known that we, CHARLES H. SISSON and SIMON P. KELCH, citizens of the United States, residing at Nelsonville, in the county 5 of Athens and State of Ohio, have invented certain new and useful Improvements in Car-Replacers, of which the following is a specification.

This invention relates to new and useful 10 improvements in car replacers or rerailers and as its principal object aims to provide a novel form of fastening device for securing the rerailers in the proper position on the ties to deflect a wheel flange from an abnormal path and guide the wheel back onto the rail.

A further object of the invention is to construct the fastening devices with such regard to proportion, number and arrangement of parts that they may not only be cheaply manufactured but will, also, be durable and efficient in service, being adapted for speedy and convenient application to the replacer blocks and the rails with a minimum expenditure of time and labor.

The above recited and other incidental objects of a similar nature, which will be hereinafter more specifically treated, are accomplished by such means as are illustrated in 30 the accompanying drawing, described in the following specification and then more particularly pointed out in the claims, which are appended hereto and form a part of this application.

Referring to the drawing, in which there has been illustrated the preferred embodiment of this invention as it is reduced to practice, and throughout the several views of which similar reference characters designate corresponding parts,

Figure 1 is a perspective view of a track section showing a pair of rerailer blocks held in operative relation to a pair of rails by means of the improved clamping devices; Fig. 2 is a transverse section taken through the track as shown in Fig. 1; Fig. 3 is a detail perspective view of one of the rerailer blocks showing the underside thereof; Fig. 4 is a detail perspective view of one of the 45 clamping devices which are employed in properly attaching the rerailer blocks to the rails.

In the embodiment of the invention shown

in the accompanying drawing, and illustrated particularly as an operative entirety 55 in Fig. 1, these are employed in connection with the rails A and B, a pair of rerailer blocks 10 and 11.

At this point it may be well to explain that, if so desired, four rerailer or replacer blocks may be used without in any way departing from the spirit of the invention. In the present instance, however, it has been found expedient to employ but two replacer blocks disposing one on the inner side of the 65 rail A and the other on the outerside of the rail B.

The members 10 and 11 are both preferably formed in the nature of steel castings and are substantially similar in construction. It will, therefore, be necessary to describe only one of the rerailers in detail, for which purpose reference will now be had to Figs. 2 and 3. The member 10 consists in a body portion 12 which is provided with 70 an arcuate upper face 13 along the outer edge of which extends a longitudinal vertically disposed flange 14. The flange 14, is, of course, adapted to deflect a wheel flange from an abnormal path as when the 75 wheels have jumped the rail. The upper face 13 of the member 10 is, as stated, longitudinally curved and is, also, inclined uniformly at all points throughout its length downwardly from the flange 14 toward the 80 rail. The purpose in thus imparting to the tread face of the body member 12 a lateral incline is to insure the movement of a wheel back onto the rail. The lower face of the body portion 12, is as shown particularly in 85 Fig. 2, recessed as at 15. Within this recess 15 and extending transversely thereof are mounted two metallic holding strips 16 and 17 which are adapted to be engaged by the jaws of the fastening devices to be later 90 described. The outer face of the body member 12 is provided with a pair of longitudinally spaced recesses, the walls 18 of which are inwardly and upwardly inclined. These recesses are adapted to receive a second pair 95 of jaws carried by the fastening devices.

While the rerailer blocks 10 and 11 are substantially similar in construction, there does exist one difference. This differentiating feature is the fact that whereas the center portion of the face 13 of the block 10

is designed to merge into the tread of the rail, as shown at the left-hand side of Fig. 2, the center portion of the face 13 of the member 11 is disposed, as shown at the right hand side of Fig. 2, below the tread of the rail B. The purpose in thus forming the members 10 and 11 so that their faces 11 will be disposed at different heights will be apparent when it is considered that the member 10 is required to move the flange of the wheel back across the tread of the rail A so that the wheel flange may engage against the inner edge of the rail, and that, on the other hand, the member 11 is required only to guide the body of the wheel back onto the tread of the rail B, to bring the wheel flange back into the engagement with the inner edge of the rail B.

The fastening devices are all similar in construction, one of them being illustrated in detail in Fig. 4. Upon reference to this figure it will thus be seen that each fastener is in the nature of a clamp and includes a body or base plate 19, one terminal of which is formed with a longitudinal bifurcation 20. The arm portions 21 and 22 produced by this bifurcation are terminally bent at right angles to form fixed jaw members 23 and 24.

On that terminal of the body plate 19 opposite to the fixed jaws 22 and 23 is formed an integral upstanding bracket 25. This member 25 is provided with a threaded opening through which passes a screw rod 26. The terminal of this screw rod 26 is equipped with the shoe 27 which is freely attached so that the screw rod may be rotated while the shoe is in relative fixed position. A head 28 is provided for the screw rod and is formed with diagonally extending intersecting bores 29 in which may be inserted a steel bar or rod when it is desired to rotate the screw in either applying or removing the rerailer blocks. The clamp is provided with a fixed jaw 30, the portion 31 of which extends transversely across the bifurcation 20 and is secured in position by rivets.

On the one longitudinal edge of the body plate of the clamp are formed a number of laterally extending sharpened spurs or teeth 32 the function of which will be hereinafter disclosed.

Having thus described the actual arrangement and construction of the rerailer blocks and the clamps employed in connection therewith, it now remains to describe the manner in which the clamps are applied for holding the members 10 and 11 in the desired position with respect to the rails A and B.

Briefly the operation is as follows: The rerailer block 10 or 11 as the case may be,

is applied to the rail with the flange 14 remote therefrom. The body plate of the clamp is then passed beneath the rail and the rerailer block. The pair of fixed jaws 21 and 22 are arranged to engage the lower edge of the body 12 being seated in the recesses at the lower edge thereof, as shown in Fig. 1 particularly. At the same time the jaw member 30 is engaged with that edge of the holding strip 16 or 17, as the case may be, which is remote from the center of the rerailer block. The spurs 32 are then engaged with the side of the adjacent tie. It now remains to insert a metal rod, or any other equivalent instrument, in the head of the screw rod and by rotating this member to clamp the shoe 27 against the adjacent face of the rail web. It will be obvious that by manipulating the screw rod the jaws 21 and 22 will firmly engage the inner edge of the member 12 against the adjacent face of the rail web. Thus the rerailer block may be held firmly and securely against the base and web of the rail. The jaws 29 of the pair of fastening devices for each rerailer block are oppositely arranged so that the blocks will be held against longitudinal movement against the impact of a car wheel coming in either direction along the track.

From the foregoing description it will now be seen that there is provided a block which is not only a simple and efficient form of rerailer block but is, also, so designed that a clamp of the simplest possible construction may be utilized in properly securing it against both longitudinal and lateral movement with respect to the rail.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in details of construction, proportion and arrangement of parts may be resorted to, when required without sacrificing any of the advantages of this invention, as defined in the appended claims.

Having thus described the invention, what is claimed as new is:

1. A rerailer of the character described including a rerailer block having a recess formed in its lower face and holding plates mounted therein, a removable clamp for detachably engaging the block against a rail, said clamp being provided with fixed jaws engageable with the block, a jaw engageable with one of the holding plates, and a movable jaw adjustable toward and away from

and engageable with the rail to which the block is applied.

2. A rerailer of the character described including a rerailer block, a holding plate carried thereby, and a removable clamp for detachably engaging the block with the rail, said clamp including a body plate, a pair of fixed jaws formed thereon and engageable with the block, an additional fixed jaw extending at right angles to the first mentioned jaws and engageable with a holding plate, and a movable jaw engageable with the rail to which the block is applied.

3. A rerailer of the character described including a rerailer block, and a removable clamping member, said clamp including a body plate having a longitudinal bifurcation at one terminal, a pair of fixed jaws formed by bending the terminals of the arms produced by the bifurcation at approximate right angles to the body plate, an additional fixed jaw traversing the bifurcation and secured to the body plate, and a movable jaw located at that terminal of the body plate opposite the first mentioned jaws.

4. A rerailer of the character described including a rerailer block, and a removable clamping member, said clamp including a body plate having a longitudinal bifurcation at one terminal, a pair of fixed jaws formed by bending the terminals of the arms produced by the bifurcation at approximate right angles to the body plate, an additional fixed jaw traversing the bifurcation and secured to the body plate and extending at right angles to the first mentioned jaw, and a movable jaw located at that terminal of the body plate opposite the first mentioned jaws.

40 5. A rerailer of the character described including a rerailer block having a recess formed in its under face, a pair of holding plates extending transversely across the recess and terminally engaged with the block, a pair of clamping members for detachably securing the block against a rail, each of said clamping members including a pair of fixed jaws engageable against the outer face of the block, a movable jaw engageable against the rail to which the block is applied, and an additional fixed jaw which extends at right angles to the first fixed jaws and is engageable with a holding plate, the second mentioned fixed jaws of the two clamps being engageable against opposite edges of the holding plate, whereby the block is held against longitudinal movement.

6. A rerailer of the character described including a rerailer block, and removable clamping members independent of the block for detachably engaging the same with a rail, each of said clamping members being provided with a pair of fixed jaws for hold-

ing the block against lateral movement with respect to the rail, and an additional fixed jaw for holding the block against longitudinal movement with respect to the rail.

7. A rerailer of the character described including a rerailer block, and clamping members independent of the block for detachably engaging the same against a rail, each of said clamping members being provided with a pair of fixed jaws engageable with the block and against the outer face thereof, a movable jaw engageable with the rail, said movable jaw co-acting with the said fixed jaws for clamping the block against the rail and for holding it against lateral movement with respect thereto, and an additional fixed jaw carried by each of the clamping members and engageable with the block, said additional jaws extending at right angles to the first mentioned jaws and co-acting with each other in holding the block against longitudinal movement with respect to the rail.

8. A rerailer of the character described including a rerailer block, and a clamp for detachably engaging the block with the rail, said clamp including fixed and movable jaws for holding the block against longitudinal and lateral movement with respect to the track.

9. A rerailer of the character described including a block member, and a clamp for detachably engaging the block with the rail, said clamp including coacting fixed and movable jaws for holding the block against lateral movement with respect to the rail, and a fixed jaw for holding the block against longitudinal movement with respect to the rail.

10. A rerailer of the character described including a rerailer block having a recess formed in its lower face, a holding plate mounted therein, and a removable clamp for detachably engaging the block against the rail, said clamp including a fixed jaw engageable with the block, a movable jaw engageable with the rail, and a fixed jaw engageable with the holding plate.

11. A rerailer of the character described including a rerailer block, a pair of holding plates carried by the base portion thereof, and a clamp for detachably engaging the block against a rail, said clamp including a fixed jaw engageable with the block, a movable jaw engageable with the rail, said fixed and movable jaws coacting to hold the block against lateral movement, and a fixed jaw adapted to be engaged with either holding plate for maintaining the block against longitudinal movement in either direction.

12. A rerailer of the character described including a rerailer block, a pair of longitudinally spaced transversely extending hold-

ing plates carried by the base portion of the block, and a detachable clamp for engaging the block against the rail, said clamp including fixed and movable jaws engageable with 5 the block and rail for holding the block against lateral movement with respect to the rail, and a fixed jaw selectively engageable with either of the holding plates for resisting end thrust received by the block from 10 either direction, whereby the block may be

held against longitudinal movement with respect to the track.

In testimony whereof we affix our signatures in presence of two witnesses.
